OTHER PUBLICATIONS

U.S. Appl. No. 29/301,735, Applicant Ji-Young Lee et al., filed Mar. 14, 2008, title Portable Telephone.

(Continued)

Primary Examiner — Jeffrey D Asch(74) *Attorney, Agent, or Firm* — Wood, Herron & Evans, LLP(57) **CLAIM**

The ornamental design for a portable telephone, as shown and described.

DESCRIPTION

FIG. 1 is a top front perspective view of a portable telephone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
